PENDANT OR THE LIKE

Carl Schraysshuen, Providence, R. I., assignor to
Carl-Art, Inc., a corporation of Rhode Island

Application May 5, 1950, Serial No. 9,737

Term of patent 7 years

(Cl. D45—15)

To all whom it may concern:

Be it known that I, Carl Schraysshuen, a citizen of the United States, residing at Providence, in the county of Providence and State of Rhode Island, have invented a new, original, and ornamental Design for a Pendant or the like, of which the following is a specification, reference being had to the accompanying drawing, constituting a part hereof.

Fig. 1 is a side elevational view of a pendant or the like, showing my new design; and

Fig. 2 is an end view thereof.

I claim:

The ornamental design for a pendant or the like, substantially as shown.

CARL SCHRAYSSHUEN.
